UNITED STATES PATENT OFFICE.

JOHN A. McGREW, OF ALBANY, NEW YORK.

RAIL JOINT.

Application filed April 6, 1929. Serial No. 353,136.

This invention relates to joints for railroad rails and more particularly to a combination joint and tie plate construction.

It is a general object of the present invention to provide a novel and improved form of rail joint.

More particularly it is an object of the invention to provide a rail joint in which the joint plates are secured to the rails by a single bolt.

One of the features of the invention comprises the use of extremely short joint plates, each having a lower flange overlying and extending beyond the rail base and being secured to the tie plate.

Another feature of the invention comprises a rail joint in which overlying flanges on the joint plates are resiliently secured to a tie plate.

Still another feature of the invention comprises the use of joint plates which engage beneath the heads of the rail ends only adjacent the ends and which engage the rail bases only near the ends of the joint plates and in which the joint plate flanges which overlie the rail bases are secured at their outer edges and ends to a tie plate.

Other and further features and objects of the invention will become more apparent to those skilled in the art upon a consideration of the accompanying drawings and following specification, wherein is disclosed a single exemplary embodiment of the invention with the understanding however that such changes may be made therein as fall within the scope of the appended claims without departing from the spirit of the invention.

In said drawings:

Figure 1 is a section on line 2—2 of Fig. 2 with the left hand joint plate shown in partial section on line 2^a of Fig. 2;

Figure 2 is a side elevation of the rail joint;

Figure 3 is a section on line 3—3 of Fig. 1; and

Figure 4 is a section on line 4—4 of Fig. 1.

The present invention contemplates the provision of a rail joint of a novel character in which, contrary to the usual practice, the abutting ends of the rails are positioned over a tie and are supported on a tie plate.

Splice bars or joint plates are used, but they function not in the customary manner, in an attempt to provide a continuous beam effect at the joint but by the provision of a true simple beam by causing the joint plates

to rest on the rail bases only near the ends of the joint plates and by having them engage under the rail heads only adjacent the ends of the rails. In this manner the wear incident to the usual movement between parts is very materially reduced and the joint lasts longer as well as being more rigid during its useful life. The joint is combined with a tie plate and fastening means in order that the whole may be secured to the tie over which the joint is made. The tie plate can be provided with any conventional means for permitting it to be secured to the tie, and spring means are provided to engage between the tie plate and the overhanging flanges on the joint plates to secure the rails down to the tie.

Referring to the drawing it will be seen that the joint is made above a tie plate 10 so that the ends 11 and 12 of the rail sections 13 and 14 rest above the center of the tie plate 75 and are spaced apart the amount required by the necessary allowances for expansion and contraction. The tie plate has a thickened portion beneath the rail bases and the thinner edge portions 15 which may be perforated as 80 at 16 to receive spikes or lag screws for attaching the plate to a tie.

The thickened portion of the tie plate has a flat seat 17 for the rail bases. The rails are adapted to have their ends held against transverse movement in respect to each other and against relative depression by means of splice bars or joint plates indicated by the reference character 18. They fit in the fishing spaces of the rails and each has a thickened bulbous 90 head 19 the upper surface of which has the ends chamfered away as at 20 so that the only engagement with the rail heads is between the points indicated by the reference characters 21 or, in the words of the claims only near 95 the rail ends. At their lower edges the joint plates have the integral flanges 22 which overlie the rail bases and extend some distance beyond them where they are reinforced as at 23. These flanges are cut away on their under 100 surfaces between the ends as shown at 24 in Figure 4 so that they engage the rail base only between the points 25 and the ends of the plates as at 26. Thus the joint plates are supported only at their ends.

The more or less three-point contact between each splice bar and its corresponding rail portions causes the splice bar to act as a simple beam supported at its two ends and carrying a load at its center. In this manner 110

the whole rail and splice member assembly is not relied on to act as a continuous beam and much better results are attained.

The joint assembly is adapted to be secured 5 down to the tie plate by resilient keys. To effect this the tie plate is provided with a pair of ribs 27 which extend vertically upwardly at the junctions between the thickened portion and the thinner edge sections and extend 10 for the full width of the tie plate. They are each provided with the inturned or overhanging head portion 28 which extends partially over the bulbous reinforcing rib 23 at the lower edge of the flange on the corresponding 15 joint plate as clearly shown in Fig. 1.

A pair of spring keys is provided to secure each joint plate flange to the tie plate. Each key is formed of an angular section of spring steel having the substantially vertical wing 30 20 and the inclined wing 31 at an obtuse angle to the vertical one. When positioned as shown in Fig. 1 the edge 32 of the inclined wing bears on the face of the joint plate flange above where it rests on the rail base. The 25 upper face of this portion 31 bears under the tip edge 33 of the overhanging head portion 28 of the rib while the bottom face 34 of the vertical wing 30 bears on a specially prepared inclined surface 35 on the tie plate beneath 30 the overhanging head 28. The inclination of the surfaces 35 is shown best in Figure 3 and the corresponding inclination of the edge faces 34 is shown in Fig. 2. Two of these keys 35 cooperate with each rib as shown in Fig. 2 so that as they are driven inwardly the correspondingly inclined portions 34 and 35 raise the vertical wing 30 and cause a flexure of the wing 31 about the fulcrum edge 33 so that a considerable pressure results on the upper 40 face of the flanges 22 adequately securing the whole joint assembly to the tie plate. It is further to be noted that these resilient keys bear on the flanges 22 only above the portions of the flanges which bear on the rail bases.

45 The joint plates are held within the fishing spaces of the rails by means of the single transverse bolt 40 having the head 41 bearing against one joint plate and receiving on the other end the lock washer 42 and nut 43. 50 Preferably the bolt passes through a hole formed by two arcuate notches 44 in the ends of the rail webs and clears these webs. It is preferable to have more or less elliptical holes 45 in the joint plates for the passage of 55 the bolt.

The combination joint and attachment device just described is extremely simple to apply since but one bolt must be inserted and the four keys can readily be driven with a 60 sledge to not only form a tight joint but can be so adjusted as to accurately effect gauging of the rails without requiring that the spikes or bolts securing the tie plate to the tie be withdrawn which effects a great saving in 65 ties since each time a regauging take place

in the usual manner additional fibers of the tie are injured and its strength is materially reduced. The joint functions in a manner different than that of the standard forms of joint and in addition to its low cost offers 70 much improved service.

Having thus described the invention, what is claimed as new and desired to be secured by Letters Patent is:

1. In a rail joint, in combination, a tie plate 75 having a base and an overhanging rib, abutting rail ends on said plate, joint plates secured to said rail ends, said plates being of a length substantially equivalent to that of the tie plate, flanges on said joint plates overlying the rail bases, one of said flanges being beneath the overhang of said rib, and a key 80 between said rib and overhang.

2. In a rail joint, in combination, a tie plate adapted to be secured to a single tie 85 and to receive the abutting ends of a pair of rails, a rib on said plate on each side of the rail bases and having a flange overhanging toward the rails, joint plates in the fishing spaces of the rails, flanges on said joint plates 90 overlying the rail bases and extending under said overhanging flanges, resilient means extending between each overhanging flange and the corresponding joint plate flange to hold the rails to the tie plate, and a single bolt 95 securing said joint plates together and passing between the rail ends.

3. In a rail joint, in combination, a pair of substantially abutting rail ends, a pair of joint plates, said joint plates engaging the fishing surface beneath the rail heads only near the rail ends, flanges on said joint plates overlying the rail bases and engaging said bases only remote from the rail ends, a single bolt securing said joint plates together and 100 passing between said rail ends, a tie plate beneath said rail ends and spring means alone clamping said joint plate flanges to the tie plate.

4. In a rail joint, in combination, a tie 105 plate, means therein to receive fastening means to secure said plate to a tie, a thick central portion adapted to receive the bases of rail ends, joint plates in the fishing spaces of said rail ends and bearing beneath the heads only at their ends, flanges on the joint plates bearing on the bases only at the ends of the flanges and means resiliently securing said flanges to said tie plate and bearing on the flanges only above their bearing on the 115 rail bases.

5. In a rail joint, in combination, a tie plate having a central portion to receive the bases of rail ends, joint plates for said rails, a single bolt holding said plates to said rails, said plates engaging under the rail heads only at the center of the plates, flanges on said joint plates engaging the rail bases only at the flange ends, ribs on said tie plate having portions overhanging said joint plate 125 130

flanges and resilient keys between said ribs and flanges to secure the joint assembly to the tie plate.

6. In a rail joint, in combination, a tie plate having a central portion to receive the bases of rail ends, joint plates for said rails, a single bolt holding said plates to said rails, said plates engaging under the rail heads only at the center of the plates, flanges on said joint plates engaging the rail bases only at the flange ends, ribs on said tie plate having portions overhanging said joint plate flanges and a resilient key between each rib overhang and the portion of each joint plate flange which engages the rail base.

7. In a rail joint, in combination, a tie plate having a central portion to receive the bases of rail ends, joint plates for said rails, a single bolt holding said plates to said rails, said plates engaging under the rail heads only at the center of the plates, flanges on said joint plates engaging the rail bases only at

the flange ends, ribs on said tie plate having portions overhanging said joint plate flanges, and a pair of keys for each flange adapted to be driven from the ends thereof between the flange and overhang.

8. In a rail joint, in combination, a tie plate having a central portion to receive the bases of rail ends, joint plates for said rails, a single bolt holding said plates to said rails, said plates engaging under the rail heads only at the center of the plates, flanges on said joint plates engaging the rail bases only at the flange ends, ribs on said tie plate having portions overhanging said joint plate flanges, a spring key for each end of each joint plate flange and means whereby each key engages the flange, the overhang and the tie plate base.

In testimony whereof I hereunto affix my signature.

JOHN A. McGREW.
